UNITED STATES PATENT OFFICE.

CHARLES MORRIS JOHNSON, OF AVALON, PENNSYLVANIA.

FURNACE CONSTRUCTION.

1,329,907.

Specification of Letters Patent.

Patented Feb. 3, 1920.

Application filed November 19, 1919. Serial No. 339,236.

To all whom it may concern:

Be it known that I, CHARLES MORRIS JOHNSON, residing at Avalon, in the county of Allegheny and State of Pennsylvania, a citizen of the United States, have invented or discovered certain new and useful Improvements in Furnace Construction, of which improvements the following is a specification.

10 My invention relates to the sealing of furnace chambers, and particularly chambers wherein a non-oxidizing atmosphere is to be maintained; and, since the difficulty in maintenance of an atmosphere of this character is 15 peculiarly acute in continuous furnaces, where the charge is carried in and out while the processes accomplished are going on uninterruptedly within the chamber, my invention finds its chief and immediate application in continuous furnaces. But it is not limited, in its application, to continuous furnaces, nor even to metallurgical furnaces—although it is chiefly in the field of metallurgy that closed chambers containing non- 20 oxidizing atmosphere maintained at high temperature are employed.

It is common in continuous furnace structure to seal the edges of moving parts with some inert mobile material, in order to cut 25 off ingress of air. It is common to use dry sand as a sealing material; but such a seal is imperfect; some air percolates through the seal; and, besides, the sand, escaping from its container, is often a source of annoyance and difficulty, working between conveyers opening air spaces, and causing wear of parts.

30 My invention in broadest aspect consists in employing a carbonaceous material, as distinguished from an inert material,—a material which under the conditions obtaining in service has avidity for oxygen—a substance which burns; and which, combining, by burning, with such oxygen as otherwise 35 would percolate through the seal, renders the so modified air, gaining access to the furnace chamber, non-oxidizing. It may even be reducing. As to the combustion and consequent consumption of the sealing material, it is a relatively slow process, for the 40 quantities of air which gain ingress are small, and the material used may be augmented with new supplies from time to time, and the seal so maintained will meet the 45 needs of practice.

I do not limit myself to any particular

reducing material, but manifestly a carbonaceous material is preferable, if only on the score of cost; and, of carbonaceous materials, I have found coke dust to suit my 60 purposes well. The coke dust I employ is preferably screened, in preparation for use, through a 15-to-the-inch screen, or thereabout. Coke dust I find is not objectionable as sand is when it escapes from its container. For, unlike sand, particles of coke are readily crushed still finer by pressure and so coke does not, as sand does, lodge between conveyers and open-air spaces between them, but rather whatever finely 70 crushed coke may lodge between containers will act upon whatever air might otherwise find ingress, after the same manner in which it acts in the sealing trough. That is to say, it will combine with oxygen and so prevent 75 bad results. Furthermore, particles of coke will not abrade as do particles of sand. The effect in steel heating furnaces is to keep down scale loss. In high speed steel 80 much valuable tungsten is lost by scaling in present-day operations.

I shall, for purposes of illustration, now describe my invention in application to a reduction furnace—a furnace such as I have found useful for the reduction of tungsten 85 ore—but I do not mean to limit myself to such a furnace, nor even to a reduction furnace; manifestly, the invention is applicable to annealing furnaces as well, and indeed 90 it is applicable to the sealing of any chamber for any purpose, where there is the possibility that air may have access and within which a non-oxidizing atmosphere is to be maintained.

Referring to the drawings, Figure I is a 95 view in transverse vertical section of a furnace of a kind known as the Bailey electric furnace, this being a furnace which I have found suitable for the reduction of tungsten ore. My invention is applied to this furnace 100 as presently will be explained. Fig. II is a similar view through the cooling chamber of the same furnace. Fig. III is a view in horizontal section through the furnace. In Fig. III the planes of section of Figs. I and II 105 are indicated by the lines I—I and II—II, respectively, and in Figs. I and II, the plane of section of Fig. III is indicated by the lines III—III.

The furnace includes the heating chamber proper 1, and the continuation of it in 110 the cooling chamber 2. It is a continuous-

furnace, and, accordingly, Fig. III indicates that both portions are of indefinite extent and that they are intercommunicating. Conveniently, a succession of cars 3, traveling 5 on rails 4 carries the charge through the furnace, advancing in the direction indicated by the arrow *a* (Fig. III), that is, in the direction from the heating chamber to the cooling chamber.

10 The characteristic of the Bailey furnace is that it is heated by an electric current traversing a mass of broken or granular carbon. The preferred arrangement is shown in Figs. I and II. The mass of carbon is 15 carried in two troughs 5, extending longitudinally along either side of the furnace chamber and in intermediate position in the height of the chamber. The car 3 travels at lower level, centrally of the chamber and between the heating elements 5. Along their 20 sides the cars are provided with troughs, 6, and into these troughs aprons 7 depend. Sealing is afforded by a suitable sealing material contained in these troughs and covering the depending edges of aprons 7. Beyond the heating-chamber, the depending edges of the cooling chamber (which is merely a screen arched over the platforms of the cars and covering their load) take the 25 place of aprons 7 and continue the seal. It will be seen that the succession of cars, abutting closely one against another, complete a substantially continuous partition across the furnace chamber, limiting the heating region to the space above the cars and protecting the running gear from undesired high temperatures. The car platform, exposed as it is to high temperature, is shown to be faced with fire brick. The leakage to 30 be guarded against is through this partition, made up as it is partly of stationary, partly of moving, members, and it is at the point of union of station with movable members that the seal is provided. The sealing substance here employed, and in which my invention consists is a granular oxidizable substance, ordinarily carbonaceous, and preferably coke. The furnace chamber then is, as a matter of fact, not the whole space within 35 the masonry, as indicated in Fig. 1, but only so much of that space as lies above the partition formed by troughs 5, car 6, and flanges 7.

The Bailey furnace used as I use it, for 40 reducing tungsten ore must be operated at higher temperature than when used as an annealing furnace. I have made no experiments, to determine the limits of temperature under which my invention may be enjoyed; but it will be apparent that, wherever 45 the temperature is great enough to bring the

granular sealing material to a point at which it will combine with the oxygen of such quantities of air as percolate through, and by so combining will mitigate or eradicate the bad effects otherwise consequent upon the ingress of air, my invention is realized. In point of fact, under the conditions which obtain in my practice now described, the heat is such in intensity and 65 the quantity of air seeking entrance is so small and its movement so slow that the gas which actually enters the furnace chamber is largely carbon monoxide, a reducing gas. The drawings show the furnace charge to 70 be a quantity of cylindrical cases, or capsules. These were adopted for my particular metallurgical operation (the reduction of tungsten ore) after I had procured a Bailey furnace for the purpose, but before 75 I had made my invention. I then found the entering air to interfere with and measurably to defeat the reduction intended, and it was to protect the furnace charge against air while still subjecting it to the temperature generated, that I inclosed it in such 80 capsules. Such protection was adequate, but the air which gained access still, under the elevated temperature, attacked the substance of the capsules, so that they were 85 very short-lived. My invention followed. Employing it, destruction of the capsules is eliminated, and, more than that, I find it no longer necessary to inclose the charge in tight capsules; it may lie in troughs or boats, 90 exposed to heat radiation from the reverberatory roof. I show the capsules, however, to aid in an understanding of the invention.

I claim as my invention:

1. A seal for the meeting edges of the walls of a heated chamber consisting of a body of granular material having avidity for oxygen. 100
2. In a continuous furnace for metallurgical operation the combination of a movable member and a stationary member provided with a tongue-and-groove shaping of contiguous edges, and a body of coke dust contained within the groove and into which the tongue extends, substantially as described. 105
3. The method herein described of overcoming the ill effects of air ingress within a furnace chamber which consists in causing the entering air to percolate through a body of material having avidity for oxygen. 110

In testimony whereof I have hereunto set my hand.

CHARLES MORRIS JOHNSON.
